ATTORNEY

UNITED STATES PATENT OFFICE

RAYMOND W. JEWELL, OF BINGHAMTON, NEW YORK

STAPLE

Application filed November 4, 1926. Serial No. 146,174.

My invention relates primarily to the provision of a novel staple for securing together the abutting edges of sheets of plaster board or "compo" board, or other building material used in wall and like construction.

The primary object of my invention is to provide a staple which clinches the boards from the rear side thereof so as not to be visible from the front, thereby eliminating the unsightliness of common staples and other devices in use, which are driven in from the front side, and frequently resulting in spoiling of the board at the point of driving.

15 Another object is to provide a staple which will at all times closely bind or clinch the adjacent edges of the board tightly together regardless of shrinkage or warping either of the boards or their support.

20 Other objects and advantages in details of construction and operation will be apparent as the description proceeds, reference being had to the accompanying drawing wherein like reference numerals indicate like parts.

25 Figure 1 is a detail perspective view of my improved staple.

Figure 2 is a detail front view of a portion of a wall, illustrating the application of my staple.

30 Figure 3 is a detail top plan view partly in section illustrating clearly the method of use of the staple.

In recent years, there has come into general use in the building trade a plaster board or "compo" board, which is rapidly being substituted for the ordinary plaster heretofore used. This plaster board generally comes in sheets of given widths and is secured to the vertical supporting studs comprising the framework of the structure. Due to the fact that these sheets of plaster boards must be secured together edge to edge, considerable difficulty has arisen in their practical use for the reason that when the sheets

40 are nailed or otherwise fastened to their supporting studs from the front side, there are left in full view, the heads of the staples or nails, frequently rendered more unsightly by the hammering resulting in abrasive marks on the board itself. Furthermore, it

has been found practically impossible in the method now in use, to secure the sheets of plaster boards to their support in such a manner that upon shrinkage of the support or warping or pulling away thereof, the edges of the plaster board sheets will not pull away from each other, leaving a crack or opening between them. Various means have been tried to overcome this difficulty, but the most effective means so far has been the covering of the crack or opening by means of panels secured to the compo board.

By my invention, I eliminate the necessity of such panels and of all the unsightliness above described.

In the drawing, the reference numeral 1 refers generally to my improved staple comprising the relatively thin, flat surface 2, provided centrally with the elongated opening or slot 3, and at either end with the prongs 4, tapered to sharp points. It will be observed particularly with reference to Figure 3, that the outer surface of the prongs 4 lies at right angles to the surface of the flat body portion 2, whereas the inner surface of the prongs 4 are tapered from the body portion 2 down to the point.

Obviously this staple may be formed by stamping the same out of flat stock, shearing the points to the configuration shown and bending them downwardly to the position clearly shown in Figures 1 and 3.

5 indicates a supporting stud to which is to be secured the abutting edges of the sheets 6 and 7 of plaster board or other material. My improved staples 1 are first secured to the support 5 by means of headed nails 8, extending through the elongated openings 3 in the staples into the support 5. In securing the staple 1 to the support 5, the prongs 4 are thus projecting outwardly to receive the pieces of plaster board 6 and 7, which are pushed or driven onto the prongs 4 as shown clearly in Figure 3. The sheets of plaster board 6 and 7 are driven onto the prongs 4 of the staples 1 in such manner that the abutting edges of the board lie in close contact with each other as at 9. The bevelled inner surfaces of the prongs 4 tend to bind the edges

of the boards 6 and 7 tightly together during the driving operation.

If now there should be a shrinkage or warping or other distortion on the part of the supporting stud 5, the elongated opening 3 in the staple 1 will permit such shrinkage or distortion relative to the staple 1, without effect upon such staple, which is thus left free of such motion, to hold and clinch the abutting edges of the boards 6 and 7 tightly together, thus preventing the opening up of a crack between these abutting edges of the boards. A filler or panel is therefore unnecessary at the abutting edges of pieces of plaster boards when my improved staples are used.

By my invention, I have provided means whereby adjacent sheets of plaster board may be securely clinched together edge to edge, without danger of the edges pulling away due to shrinkage and other causes, and leaving the front sides of the boards free of markings or unsightly fastening means.

By the terms "plaster board" or "compo board", I have referred to any form of composition board material of well known make, used for the purpose described.

Of course my improved staple is obviously adaptable to many other uses, and to changes in form without departing from the spirit and scope of my invention. I do not limit myself therefore to the exact form and use herein shown and described, other than by the appended claim.

35 I claim:—

A staple comprising a flat body portion having an elongated opening therein, prongs at the ends of said body portion, said prongs having an outer surface at right angles to 40 said body portion and an inner surface tapering from said body portion to the free end of said prongs.

RAYMOND W. JEWELL.
